BLUE FLAME OIL BURNER

Charles M. Stroud, Minneapolis, Minn.

Application December 18, 1935, Serial No. 55,018

6 Claims. (Cl. 158—86)

This invention relates to a liquid fuel burner and particularly to an oil burner of the blue flame type.

Such burners of the blue flame type usually comprise a member having recesses with wicks therein to which oil is supplied and perforated cylinders extending above said member forming annular passages communicating with said recesses through which oil vapor passes upwardly. 10 In starting such burners the same have heretofore burned with a high red flame until the burner became heated to a certain degree when a blue flame would be produced.

It has heretofore been the practice to have a 15 passage of rather large extent for vapor constantly supplied with oil or vapor and burning to constitute a pilot.

It is an object of this invention to provide a 20 simple and efficient construction of blue flame burner in which the initial burning with a red flame is eliminated and in which a blue flame can always be had.

It is a further object of the invention to provide a 25 novel and efficient means comprising a passage of small cross sectional area for oil vapor, which vapor mixed with air can burn at the top of said passage to form a pilot.

It is another object of the invention to provide a 30 burner having a burner member with oil receiving recesses therein and a vaporizing chamber extending below said recesses, a plurality of superposed disks of fibrous material being disposed in said chamber, which disks are preferably provided with holes arranged in staggered relation 35 in adjacent disks.

It is still another object of the invention to provide a 35 burner having a novel form of baffle means at the top of the perforated or screen cylinders used together with novel means for supporting 40 such baffle.

These and other objects and advantages of the 45 invention will be fully set forth in the following description made in connection with the accompanying drawing, in which like reference characters refer to similar parts throughout the several views and in which:

Fig. 1 is a vertical section taken substantially 50 on line 1—1 of Fig. 2 as indicated by the arrows;

Fig. 2 is a top plan view of the burner with the 55 baffle means removed;

Fig. 3 is a view in side elevation of the member used in the vaporizing chamber;

Fig. 4 is a top plan view of the member shown 55 in Fig. 3;

Fig. 5 is a plan view of one of the disks used; and

Fig. 6 is a section taken on line 6—6 of Fig. 5 as indicated by the arrow.

Referring to the drawing, a burner structure 5 is shown comprising a member 10 having a plate-like bottom throughout most of its extent from which project equally and circumferentially spaced and apertured lugs 10a adapted to receive bolts to secure said member in place. Member 10 has formed therein a pair of annular grooves 10b and 10c which extend adjacent its outer edge in radially spaced relation. The walls extending about grooves 10b and 10c are reduced in thickness and have formed thereon shoulders 10d some 15 distance from their upper ends. Cylindrical perforated cylinders or screens 11, 12, 13 and 14 surround said reduced portions respectively and rest at their lower ends on the shoulders 10d. Cylinders 11 to 14 extend vertically quite a distance 20 above member 10. Wicks 15 will be disposed in the grooves 10b and 10c and said grooves are connected by passages 10f extending through arms 10j which join the adjacent walls of said grooves. Member 10 has formed at its central portion a 25 cylindrical casing 10g which extends downward quite a distance from the flat bottom portion of member 10. Casing 10g has a chamber therein and this communicates through passages 10h with groove 10c, passages 10h being formed in arms 30 10i which extend between the inner wall of groove 10c and casing 10g. A cylindrical member 16 shown in Figs. 3 and 4 is disposed in the chamber in casing 10g. Member 16 is open at its upper end and its bottom and side walls have therein a 35 multiplicity of small holes 16a. The bottom of member 16 is spaced a short distance from the bottom of the chamber in casing 10g and said casing has at its lower end a threaded boss 10j adapted to receive a fuel supply pipe for supplying 40 oil to casing 10g. The member 16 has disposed therein quite a number of disks 17. One of these disks is shown in Figs. 5 and 6 and it will be seen that the same has extending therethrough a plurality of equally and circumferentially spaced 45 holes 17a. When the disks 17 are arranged in member 16 as shown in Fig. 1 the holes 17a will be arranged in staggered relation. A cap member 18 has an exteriorly threaded flange screwed into the top of casing 10g so that member 18 forms a 50 cover for said casing. A rod 19 extends upwardly from a central boss on member 18, the same having its lower end threaded into said boss and a baffle member 20 has a central depending boss 20a with a bore therein into which rod 19 extends so 55

that baffle 20 rests on said rod. Baffle 20 has a depending cylindrical flange 20b which extends to a point slightly below the top of cylinders 11 to 14. Baffle 20 has another cylindrical flange 20c which extends downwardly quite a distance below the top of cylinders 12 and 13 and substantially midway between the same. Baffle 20 has an inwardly and upwardly curved flange 20d at its central portion and a plurality of openings 20e are formed between this flange and flange 20b, the space between said flanges being almost entirely open and only traversed by narrow ribs 20f. Baffle 20 also has an upwardly and outwardly extending outer flange 20g. Flanges 20d and 20g extend oppositely in symmetrical relation to depending flange 20c. The outer cylinder 11 also has an upwardly and inwardly extending baffle member 21 supported on its upper end. This baffle member is of annular form extending entirely around cylinder 11. A similar baffle 22 is supported on the upper end of inner cylinder 14, this baffle extending upwardly and outwardly toward baffle 20c. As shown in Fig. 1 baffles 20d, 20g, 21 and 22 are of curved formation. Baffle 21 has upwardly standing therefrom supporting lugs 21a having V-shaped recesses in their upper ends and baffle member 20 has circumferentially spaced legs 20h having V-shaped lower ends adapted to rest on the upper ends of lugs 21a. Baffle 20 is thus additionally supported on baffle 21.

Member 10 also has depending from one side a comparatively small cylindrical casing 10k internally threaded at its lower end to receive a fuel supply pipe indicated as 23. A hole 10m is formed in the bottom of groove 10b which extends into the chamber in casing 10k. A pair of plate-like lugs 10n extend upwardly from the bottom of groove 10b at each side of hole 10m and between the walls of groove 10b, said lugs extending to a line adjacent the top of said groove. A pair of perforated plates or screen members 24 are secured between screens 11 and 12 and extend to the bottom of said screen members just over or adjacent the lugs 10n. Members 24 have laterally extending lugs 24a which can be secured to the side of screen member 12 in any suitable manner as by welding. Lugs 10n and screen members 24 are spaced a comparatively short distance circumferentially so that a passage of comparatively small area extends upward between screens 11 and 12.

In operation oil will be supplied through pipe 23 in sufficient quantity to maintain oil in groove 10b between the lugs 10n which act as dams to confine a small reservoir of oil between them in groove 10b. This oil will saturate the portion of wick 12 in said groove between lugs 10n and vapor will pass upwardly between rings 11 and 12 in the passage between members 24. This vapor will mix with air and the flame formed by the combustion of this vapor and air will burn at the top of said passage or at the top of rings 11 and 12. This flame will be a blue flame and will act as a pilot light for the burner. When the burner is to be used for heating, oil will be supplied to the bottom of casing 10g and will pass through the holes in the bottom of member 16 to the disks 17. Some oil will also pass around the outer side of member 16 and through the holes in the side wall thereof to the disks 17, member 16 fitting rather loosely in casing 10g. The oil passes up through the disks 17 and through the staggered holes 17a and flows out through passages 10h and 10e to the grooves 10b and 10c saturating the 75 wicks 15. Vapor will pass upwardly in the pas-

sages between cylinders 11 and 12 and cylinders 13 and 14. It will be seen that the passages 25 between cylinders 11 and 12 and cylinders 13 and 14 thus form vapor passages while the passage 26 between cylinders 12 and 13 forms an air passage, this passage being open at the bottom of member 10 except where it is closed by arms 10f. The vapor passing upwardly in passages 25 is mixed with air which enters through the holes in the cylinders 11 to 14 and this mixture passes laterally from said passages through the outlets at the top of cylinders 12 and 13 and between the same and the ends of baffles 21 and 22. The mixture then passes through a vertical outlet or passage at either side of baffle 20c, which passages are formed between said baffle 20c and the upper ends of baffles 21 and 22. The mixture then passes upwardly at either side of baffle 20c and part of the same is directed inwardly to pass through openings 20e as indicated by the arrows 20 in Fig. 1, while a similar portion passes outwardly between the top of baffle 21 and baffle 20g as indicated by the arrows in Fig. 1. The mixture is ignited at the top of baffles 21 and 22 and will burn here with a blue flame at all times. The area of the outlet openings between the top of cylinders 12 and 13 and the inner ends of baffles 21 and 22 is substantially equal in area to the area of the passages between the inner ends of the baffles 21 and 22 and flange 20c. There is thus no choking of the flow of the mixture nor any constriction of the passage. This results in the burner burning with a blue flame even when it is initially started. As above stated burners heretofore have usually burned for a time with a high red or yellow flame.

From the above description it is seen that applicant has provided a very simple and efficient structure of blue flame burner. By having the narrow passage or chimney effect between members 24 and screens 11 and 12, a pilot can be had which is clean and not smoky and which will burn with a blue flame. The flow of the combustible mixture is efficiently controlled to secure a blue flame on the burner at all times. Baffle member 20 is supported so that it can be easily and quickly removed. The action of the disks 17 has been found in practice to be exceedingly efficient. The oil engaging these disks is, after the burner gets into operation, vaporized in member 16 so that there will be no carbon deposits in member 10 or about the wicks 15. Oil initially is supplied to the wicks 15. As the burner begins operating and member 10 becomes heated, the oil in grooves 10b and 10c is vaporized and as stated no oil passes from casing 10g into the grooves. The oil is vaporized in passing through the disks 17 so that only vaporized oil passes out through the passages 10h. This results in a great saving of the wicks which do not become encrusted with carbon at their tops. Cap 18 can be removed when desired if the disks 17 are to be replaced. The burner is simple in construction and the same has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:

1. An oil burner of the blue flame type having in combination, a burner member having spaced annular grooves therein, means for supplying oil to said grooves, pairs of perforated cylinders extending upward from said member, the spaces between the cylinders of each pair forming vapor passages communicating with said grooves at their lower ends, the space between the adjacent cylinders of said pairs forming an air passage, baffles at the top of said cylinders forming lateral outlets for said vapor passages respectively and baffle means cooperating with said baffles to form vertical and lateral outlet passages above said lateral outlets, said last mentioned baffle means having a depending portion extending into said air passage to divide the same to cause air to pass into said vertical passages in substantially equal volume. 5
2. An oil burner of the blue flame type having in combination, a burner member having spaced annular grooves therein, means for supplying oil to said grooves, pairs of perforated cylinders extending upward from said member, the spaces between the cylinders of each pair forming vapor passages communicating with said grooves at their lower ends, the space between the adjacent cylinders of said pairs forming an air passage, baffles at the top of said cylinders forming lateral outlets for said vapor passages respectively and baffle means cooperating with said baffles to form vertical and lateral outlet passages above said lateral outlets, said last mentioned baffle means having a depending portion extending into said air passage forming a vertical outlet between the same and said first mentioned baffles and having a top portion directing the vapor and air in opposite directions at each side of said depending portion. 10
3. An oil burner of the blue flame type having in combination, a burner member with a plurality of recesses therein, wicks in said recesses, burner rings above said recesses, said member having a vaporizing chamber extending below and communicating with said recesses, a plurality of superposed fiber disks disposed in said chamber each having a plurality of holes therethrough arranged in staggered relation in adjacent disks and means for supplying oil to the bottom of said chamber. 15
4. An oil burner of the blue flame type having in combination, a burner member having a pair of radially spaced annular oil receiving grooves, two pairs of perforated cylinders extending upwardly from the walls of said grooves, the spaces between the cylinders of each pair forming vapor passages and the spaces between the pairs of said cylinders forming an air passage, baffle members supported on the outermost and innermost cylinders respectively at their upper ends and extending upwardly and toward each other in curved form, a baffle member extending over all of said passages and having a cylindrical flange extending downwardly into said air passage to a point some distance below the top of said cylinders whereby the air and vapor in said vapor passages can pass laterally between the top of the two inner cylinders and the top of said first mentioned baffles and then upwardly between said first mentioned baffles and said flange and outwardly beneath said second baffle. 20
5. An oil burner of the blue flame type having in combination, a burner member with a plurality of annular grooves therein, wicks in said grooves, perforated cylinders extending above said grooves, said member having a cylindrical vaporizing chamber extending below and in communication with said grooves, a screen extending about the wall of said chamber, a plurality of superposed fibrous disks fitting in said screen each having a plurality of holes therethrough arranged in staggered relation in adjacent disks and means for supplying oil to the bottom of said chamber. 25
6. An oil burner of the blue flame type having in combination, a burner member having a pair of radially spaced annular oil-receiving grooves therein, two pairs of perforated cylinders extending upwardly respectively from the walls of said grooves, the spaces between the cylinders of each pair forming vaporizing passages and the space between the pairs of said cylinders forming an air passage, annular baffle members supported on the top of the outermost and innermost cylinders respectively and curved upwardly and toward each other with a space therebetween, a baffle member extending over all of said passages and having a trough-shaped annular top portion with an annular vertical flange depending therefrom midway between the edges of said first mentioned baffle members and extending downwardly into said air passage centrally thereof whereby the air and vapor in said vapor passages can pass laterally over the tops of the innermost cylinders upwardly between the edges of said first mentioned baffle members and then outwardly and upwardly along the under side of said trough-shaped portion. 30
